(57) The ornamental design for a housing assembly of a rope grab, as shown and described.

DESCRIPTION

FIG. 1 is a first side perspective view of a housing assembly of a rope grab according to the present invention.

FIG. 2 is a second side perspective view of the housing assembly of a rope grab shown in FIG. 1;

FIG. 3 is a front view of the housing assembly of a rope grab shown in FIG. 1;

FIG. 4 is a rear view of the housing assembly of a rope grab shown in FIG. 1;

FIG. 5 is a top view of the housing assembly of a rope grab shown in FIG. 1; and,

FIG. 6 is a bottom view of the housing assembly of a rope grab shown in FIG. 1.

The broken lines showing portions of the housing assembly of a rope grab are for the purpose of illustrating portions that form no part of the claimed design.
